US00D564872S

(12) United States Design Patent (10) Patent No.: US D564,872 S
(45) Date of Patent: * Mar. 25, 2008

(54) HANGING UTENSIL CARTON

(75) Inventor: Brian D. Kamins, Sherman Oaks, CA (US)

(73) Assignee: Custom Cutlery, Inc., Sun Valley, CA (US)

() Term: 14 Years

(21) Appl. No.: 29/275,233

(22) Filed: Dec. 18, 2006

(51) LOC (8) Cl. 09-03

(52) U.S. Cl. D9/418; D9/431

(58) Field of Classification Search D9/414-432, D9/702-710; 206/733, 769, 773, 775-777, 206/781-783; 229/162.1, 162.3, 162.6, 162.7

See application file for complete search history.

(57) CLAIM

The ornamental design for a hanging utensil carton, as shown and described.

DESCRIPTION

FIG. 1 is a perspective view of a first embodiment of a hanging utensil carton showing my new design;

FIG. 2 is a top view thereof;

FIG. 3 is a left side view thereof;

FIG. 4 is a front view thereof;

FIG. 5 is a back view thereof;

FIG. 6 is a right side view thereof;

FIG. 7 is a bottom view thereof;

FIG. 8 is a perspective view of a second embodiment of a hanging utensil carton showing my new design;

FIG. 9 is a top view thereof;

FIG. 10 is a left side view thereof;

FIG. 11 is a front view thereof;

FIG. 12 is a back view thereof;

FIG. 13 is a right side view thereof; and,

FIG. 14 is a bottom view thereof.
